UNITED STATES PATENT OFFICE

GARNET W. COEN, OF VENICE, CALIFORNIA.

HYDROCARBON-BURNER.

1,060,164.

Specification of Letters Patent. Patented Apr. 29, 1913.

Application filed February 5, 1912. Serial No. 875,662.

To all whom it may concern:

Be it known that I, GARNET W. COEN, a citizen of the United States, residing at Venice, in the county of Los Angeles and State of California, have invented new and useful Improvements in Hydrocarbon-Burners, of which the following is a specification.

This invention relates to improvements in hydrocarbon burners, and it is an object of the invention to provide a nozzle portion having tangentially arranged openings for admitting the hydrocarbon products to a circular chamber adjacent to a discharge outlet.

It is also an object of the invention to provide a burner with a nozzle having a discharge outlet and a chamber adjacent thereto having tangential inlets whereby the hydrocarbon products will be given a whirling movement before passing out through the discharge opening.

It is a further object to supply a reciprocating valve to accurately and equitably regulate the tangential slots provided with self cleaning wings registering in the slots.

In the accompanying drawing forming a part of this specification, Figure 1 is a longitudinal section of the improved burner, Fig. 2 is an enlarged transverse sectional view taken upon the line 2—2 of Fig. 1. Fig. 3 is a detail perspective view of the adjustable nozzle controlling member.

The details and features of the invention will now be more particularly described, reference being had to the said drawing in which 10 indicates a supply pipe, 11 a casing and 12 a discharge pipe. The casing 11 may be of any ordinary or desired construction, having threaded connections from the outlet pipe 12 valve stem gland and the inlet pipe 10.

The discharge pipe 12 is threaded at its outer end and adapted to receive an internally threaded cap 14 having an overhanging inwardly extending annular flange 15 for holding a nozzle in position. Within the cap 14 is located a nozzle 16 having an annular flange 17 formed upon the outer end thereof which is adapted to fit between the flange 15 of the cap and the end of the pipe 12. By screwing the cap 14 tightly in place upon said flange 17 the nozzle is centrally held in place within the bore of the discharge pipe 12 as clearly shown in Fig. 1. The body portion of the nozzle is of a sufficiently smaller diameter than the bore of the

discharge pipe 12 to provide for a passage about the said body portion, for the hydrocarbon products to be burned. The nozzle 16 is also centrally bored and the inner end of the bore is tapered as shown at 18 so as to tend to converge and direct the hydrocarbon materials toward the small discharge outlet 19. The walls of the nozzle are also formed with inlet passages 20 extending from just inside the flange 17 inwardly. To secure the desired result in the atomizing and discharging of the hydrocarbon products the inlet passages 20 are arranged tangentially with respect to the bore of the nozzle 16 so that the materials forced into the nozzle through said passages will be given a whirling tangential direction within the same and will be so concentrated upon the tapered end surface of the bore and at the discharge opening 19 that a diverging spray will be formed outside the burner and the ignited products will not be carried far from the end of the burner. The structure will result in a close cone shaped flame in burning the fuel.

In using the device the hydrocarbon materials are usually delivered in the pipe 10 to the burner under pressure and preferably also in a preheated condition, the forcing of the materials, thus further tending to impart a high velocity to the materials passing through the passages 20 to the outlet chamber, thus producing a thorough twisting or whirling of the hydrocarbon products, which, upon being released through the outlet 19, will be thoroughly disintegrated by centrifugal force and enter the furnace in a completely atomized condition.

The inlet apertures or passages of the burner may be enlarged or diminished in size. In the device shown the passages 20 are in the form of tangentially arranged slots. Movably mounted within the nozzle 16 is an adjustable member 26 having a cylindrical body portion formed with tangential projections 27 adapted to extend into the slots 20 so as to fill the same. The said member 26 is arranged to reciprocate within the bore of the nozzle, the projections 27 being also reciprocated thereby in the slots 20 for increasing or diminishing their openings. The said member 26 is also provided with a pin projection 28 adapted to pass through the discharge opening 19 when it is necessary to clean the discharge orifice. The said member 26 is also provided with a

screw threaded bore adapted to engage the threaded end 30 of a valve stem 31. The other end of the valve stem projects through a packing gland 32 in the casing 11 and is 5 provided with a handle 13 by which it may be turned. By turning said stem the member 26 may be moved back and forth in adjusting the size of the passages 20 to vary the action of the burner. By controlling the 10 area of said passages 20, the maintenance of the maximum velocity in the hydrocarbon material passing through the said passages 20 under varying initial pressures in the burner up to said passages is obtained and 15 the flow of the hydrocarbon material to the nozzle chamber may be absolutely controlled at this point without decreasing its velocity through said passages. Thus if the flow to the burner is decreased by any suitable 20 means (not shown) the pressure in the discharge pipe 12 would be decreased, resulting in a decreased velocity of the hydrocarbon forced through passages 20, thereby reducing the rotations of the material in the nozzle 25 chamber, and impairing the atomizing effect. It will thus be observed that by controlling the flow at the entrance to passages 20, the maximum pressure is always maintained at this point, and the high velocity 30 of the hydrocarbon material forced through said passages is also maintained, thus the velocity of the flow of the hydrocarbon material to the nozzle chamber may be kept constant regardless of varying initial pressures in supply pipe 12.

What I claim is:—

1. A hydrocarbon burner having a nozzle formed with a central chamber and an outlet passage, the walls of said chamber having tangential slots for admitting hydrocarbon products within the nozzle chamber, a member mounted in said nozzle and guided by said slots and adapted to partially or entirely close the said slots, and means for operating said member. 40

2. A hydrocarbon burner having a nozzle formed with a central chamber and an outlet passage, the walls of said chamber having slots extending from said outlet passage to its inner rim, a valve member to fit said chamber and provided with guides to engage and register in said slots, and means to actuate the valve member. 50

3. A hydrocarbon burner having a nozzle formed with a central chamber and outlet 55 passage, the walls of said chamber having slots extending from the outlet passage to its inner rim, a valve member to fit said chamber, a cylindrical needle point adapted to clean said outlet passage, and a screw 60 thread in said valve member adapted to engage a threaded valve stem to actuate the same.

In witness that I claim the foregoing I have hereunto subscribed my name this 25th 65 day of January, 1912.
